United States Patent Office

Des. 211,915
Patented Aug. 6, 1968

211,915

REENTRY VEHICLE OR SIMILAR ARTICLE

Frederick Raymes, Los Angeles, and Rashid M. Rashidian,
Pomona, Calif., assignors to North American Rock-
well Corporation, a corporation of Delaware

Filed Sept. 22, 1966, Ser. No. 3,954

Term of patent 14 years

(Cl. D71—1)

FIG. 1

FIG. 2

FIG. 3

FIG. 4

FIG. 5

FIG. 6

FIG. 1 is a perspective view of a reentry vehicle or similar article showing our new design with its movable wings in a substantially vertical position;

FIG. 2 is a side elevational view of the opposite side not shown in FIG. 1;

FIG. 3 is a rear elevational view thereof;

FIG. 4 is a perspective view of the reentry vehicle or similar article of FIG. 1 with its moveable wings pivoted to a substantially horizontal position;

FIG. 5 is a side elevational view of the opposite side not shown in FIG. 4; and

FIG. 6 is a rear elevational view thereof.

We claim:

The ornamental design for a reentry vehicle or similar article, as shown.
